[57] CLAIM

The ornamental design for "buckle", as shown.

DESCRIPTION

FIG. 1 is a front view of a buckle;

1 Claim, 11 Drawing Sheets

FIG. 2 is a rear view of the buckle of FIG. 1;
FIG. 3 is a plan view of the buckle of FIG. 1;
FIG. 4 is a base view of the buckle of FIG. 1;
FIG. 5 is a right side view of the buckle of FIG. 1;
FIG. 6 is a cross-sectional view taken on line A—A of FIG. 5;
FIG. 7 is a front view of a male member of the buckle of FIG. 1;
FIG. 8 is a plan view of the male member of FIG. 7;
FIG. 9 is a base view of the male member of FIG. 7;
FIG. 10 is a right side view of the male member of FIG. 7;
FIG. 11 is a cross-sectional view taken on line B—B of FIG. 7;
FIG. 12 is a cross-sectional view taken on line C—C of FIG. 7;
FIG. 13 is a front view of a female member of the buckle of FIG. 1;
FIG. 14 is a rear view of the female member of FIG. 13;
FIG. 15 is a plan view of the female member of FIG. 13;
FIG. 16 is a base view of the female member of FIG. 13;
FIG. 17 is a right side view of the female member of FIG. 13;
FIG. 18 is a cross-sectional view taken along line D—D of FIG. 17;
FIG. 19 is a front view showing the buckle attached to a belt or the like; and,
FIG. 20 is a cross-sectional view showing the buckle attached to a belt or the like.
The broken line showing of a belt, in FIGS. 19 and 20, is for illustrative purposes only and forms no part of the claimed design.
